UNITED STATES PATENT OFFICE.

ADOLPHUS W. RICH, OF MILWAUKEE, WISCONSIN.

DESIGN FOR A BUTTON-SHOE.

SPECIFICATION forming part of Design No. 33,932, dated January 15, 1901.

Application filed August 27, 1900. Serial No. 28,257. Term of patent 7 years.

To all whom it may concern:

Be it known that I, ADOLPHUS W. RICH, a citizen of the United States, residing at Milwaukee, in the county of Milwaukee and State 5 of Wisconsin, have invented and produced a new and original Design for Button-Shoes, of which the following is a specification, reference being had to the accompanying drawings, forming a part thereof.

10 Figure 1 is a side view of a shoe, showing my new design; and Fig. 2 is a front view of the same.

As shown in the drawings, the leading or material feature of my design consists of two 15 inset strips *a a*, extending on each side of a single central band *b* from the seam between the top *d* and the vamp or upper *e* over the instep to the upper edge of the top. These

inset strips *a a* are made of material contrasting with that of the top *d* and central band *b* and are stitched along their edges to the overlying edges of the central band *b*, the top *d* on one side, and the button-fly *f* on the other side, the stitches or seams giving an ornamental or finished appearance to the design. 25

Having thus described my invention, what I claim as new, and desire to secure by Letters Patent, is—

The design for a button-shoe as herein shown and described. 30

In witness whereof I hereto affix my signature in presence of two witnesses.

ADOLPHUS W. RICH.

Witnesses:

CHAS. L. GOSS,

HERBERT L. ROLOFF.
